UNITED STATES PATENT OFFICE.

JOHANN FRIEDRICH HEY, OF STRASBURG, GERMANY.

PRESSURE-REGULATOR FOR BOILERS

1,025,954.

Specification of Letters Patent.

Patented May 7, 1912.

Application filed February 3, 1910. Serial No. 541,756.

To whom it may concern:

Be it known that I, JOHANN FRIEDRICH HEY, a subject of the German Emperor, and resident of Strassburg, Alsace-Lorraine, Germany, have invented certain new and useful Improvements in Pressure-Regulators for Boilers, of which the following is a specification.

My invention relates to devices for regulating the pressure of steam coming from a boiler, by controlling the amount of steam produced, or in other words, the intensity of steam generation, for instance by altering the draft. Regulators of this character generally comprise a movable or yielding member exposed to the boiler pressure and connected directly or indirectly with the controlling device, for instance a damper. A variation in boiler pressure will thus cause a shifting of the damper or other controlling device. The indirect operation of the controlling device through the medium of a relay, that is an intermediate device governing the action of a motive agent on the controlling device, increases the sensitivity of the regulator. Still, as constructed heretofore, these regulators are not sensitive enough to produce the result contemplated by my invention, that is to say, to give the controlling device periods of operation corresponding in number and length of time to the fuel-charging periods. If, for instance, the furnace is to receive a fresh supply of fuel ten times an hour, my improved regulator will operate in periods of six minutes, for instance by opening and closing a damper which regulates the draft.

Another feature of my invention relates to a pressure-recorder that will clearly indicate the variations of pressure, which with my invention are so slight that the usual recorders would fail to show them clearly.

A specific embodiment of my present invention is shown in the accompanying drawings, in which—

Figure 1 is a side elevation of the improved-regulator, with parts in section; Fig. 2 is a front elevation thereof, partly in section; Fig. 3 is a top view; and Fig. 4 is a detail side elevation, drawn upon a larger scale than Fig. 1.

The pressure-receiving member 1 consists preferably of a series of elastic diaphragms 2 of arched structure, in contact with each other alternately at their inner and at their outer edges and connected by welding or

soldering, or fastened together in suitable manner. A bellows-like hollow elastic body is thus formed, which is known as a capsular spring of the Belleville type. This capsular spring is closed at its bottom, while its top is fitted tightly against the cover 3 of the casing 4 in which the spring is housed. The sectional construction of the capsular spring enables me to readily increase or diminish the number of sections and thereby the sensitiveness of the device. The interior of the capsular spring 1 communicates with the surrounding air by means of a central opening 7 in the cover 3. The chamber of the casing 4 exteriorly of the spring is filled with a suitable liquid and communicates, by a pipe 6, with the steam space of the boiler. To the bottom of the spring 1 is secured rigidly a rod 8, passing with some play through the opening 7 and provided with nuts 9 to variably limit its downward movement.

The movement of the capsular spring 1 and of the rod 8, under the influence of pressure variations, is utilized for the purpose of operating a controlling device, for instance a draft regulator. In the construction shown, this operation is effected indirectly, through the medium of a relay in which a separate motive agent is employed, such as water under pressure. For this purpose a crosshead 10 is secured to the upper end of the rod 8, and to this head is pivotally connected at 11 a lever 12, rigidly attached to a spindle or rock shaft 13 journaled at one end of a forked lever 14. The latter is fulcrumed at 15 upon a bracket 3^a projected from the cover 3. The pivot or fulcrum 11 of the lever 12 is not in alinement with the fulcrum 15 of the lever 14, but to one side thereof and between the axes 15 and 13. On the rock shaft 13 is further secured rigidly a lever 16, pivotally connected at 17 with a rod 18, the lower end of which has a similar connection with a lever 19. The latter, fulcrumed at 20 upon a cylinder 21 carried by the casing 4, is arranged to operate the vertically movable slide valve 23 controlling the movement of the piston 22. The levers 12 and 16 are preferably connected by a crossbar 26 passing through openings 27 in the members of the lever 14 so as to afford ample vertical play for an independent movement of the connected levers 12 and 16 relatively to the lever 14. When the controlling device is in the posi-

tion of rest, the pivotal connection 17 is in line with the fulcrum 15. The drawing shows openings 27 at each side of the fulcrum 15, so that the lever 14 may be used either in the position shown, or in the reverse position, according as the connection 34 is to the right or to the left of the fulcrum 15. The operating piston 22 is shifted by steam or preferably by a liquid (water) under pressure, such motive agent being supplied through a pipe 29 and led away through a conduit 30.

The slide valve 23 is formed with passages 24^a and 25^a which are always in communication with the inlet and outlet ports 24 and 25 of the cylinder 21. In the central position of the slide valve the ends 24^b and 25^b of the latter close the passages against the channel 29^a which communicates with the inlet pipe 29, and the central part of the slide valve closes the said passages against the channel 30^a which communicates with the outlet conduit 30. If the slide valve is shifted downward, pressure fluid flowing through the inlet pipe 29, the channel 29^a the port 24^a and the port 24 passes into the cylinder 21 and below the piston 22, so as to force the same upward, the liquid above the piston escaping through the port 25, the passage 25^a of the slide valve, the channel 30^a and the conduit 30. On the other hand, if the slide valve 23 is shifted upward, communication is established between the port 25 and the inlet pipe 29, and between the port 24 and the outlet pipe 30, so that the piston 22 is lowered.

The piston rod 31 attached to the piston 22 is provided with a crosshead 32 from which a connecting rod 33, having pivotal connections at both ends, extends to the rock shaft 13. The lever 14 is operatively connected with a device controlling the intensity of steam generation, for instance a chain 34 may connect said lever with a draft-regulating damper D arranged in the smoke flue F. Let us assume that the steam pressure increases in the boiler; the pressure being conveyed through the pipe 6 to the liquid 5, will compress the capsular spring 1 and thus move the rod 8 upward. Since the slide valve 23 is in its central position and closes both channels 24 and 25, the piston 22 can not move, and the shaft 13 forms a stationary fulcrum for the levers 12 and 16 as they are moved upward by the rod 8. The upward movement of the lever 16 lifts the connecting rod 18 and lowers the slide valve 23, allowing the motive agent to pass from the pipe 29 through the port 24 and below the piston 22, while at the same time port 25 is connected with the outlet conduit 30. The piston 22 will then rise, and since the steam pressure holds the spring 1 (and therefore the rod 8) stationary, the upward movement of the piston will cause the levers 12 and 16

to swing about the pivot 11 as a stationary fulcrum, while at the same time the lever 14 swings about its fulcrum 15. By reference to Figs. 1 and 4 it will be seen that the pivotal connections 13 and 17 are on opposite sides of the pivot or temporary fulcrum 11; therefore, when the piston 22 moves upward and raises the rock shaft 13, the pivotal connection 17 and the rod 18 will be lowered, and the slide valve 23 raised to its central position, so that the piston 22 and the parts connected therewith will be held in their raised position. The movement of the lever 14 shifts the damper connected with the chain 34, in such a manner as to reduce the activity of combustion, that is to say, the damper will be moved toward its closed position. When on the other hand the pressure decreases within the boiler, the capsular spring 1 will expand, causing the rod 8 to move downward. The piston 22 and rod 31 being stationary at this moment, the connected levers 12 and 16 will be moved downward, imparting a like motion to the rod 18 and raising the slide valve 23 to admit the motive agent from the pipe 29 through the channel 25 above the piston 22. The latter will therefore move downward, carrying with it the rock shaft 13 and causing the lever 14 to swing about the fulcrum 15 in the direction opposite to that first referred to, while at the same time the connected levers 12 and 16 are swung about the pivot 11 as a temporary fulcrum. The lever 14 shifts the damper toward the open position, thus increasing the draft and the activity of combustion, so as to restore the pressure to normal. The left hand portion of the lever 16 moves downward, but the portion to the right of the pivot 11 will move up, thus raising the rod 18 and lowering the slide valve 23 to its central position. The piston 22 is thus again held against upward or downward movement.

By increasing the number and the size of the annular elements 2 the sensitiveness of the capsular spring is augmented. The spring may therefore be made of such proportions that it will operate in accordance with the pressure variations occurring in the boiler between two successive firings or introductions of fresh fuel, with such precision as to close the damper almost entirely at the time the new charge of fuel is put in. The periods of damper movements will thus correspond in number to the periods of fuel supply. As the combustion proceeds after the introduction of fresh fuel, the steam pressure will increase somewhat and the damper will be lowered or shifted gradually in the manner described above, the proportions being so selected that it will be closed almost entirely when the time arrives for the introduction of fresh fuel, which time is governed by factors such as the

amount of fuel supplied, the grate surface, etc. Thus, when the door is opened to admit the fuel, the very least possible amount of cold air will pass through the boiler flues, thus reducing the cooling of the flues at the time of stoking to a minimum.

The usual means for recording boiler pressures consists of a diaphragm or the like exposed to the boiler pressure and operating a stylus which produces a record on a traveling sheet of well-known character. If this usual means were fitted to a boiler provided with my improved regulator, it would record an almost straight line, the variations of pressure being so slight as not to appear clearly in such record. If, therefore, it is important to obtain a clear record of these variations, however slight (as when it is desired to investigate the combustion process thoroughly), it becomes necessary to provide a different recording means in connection with my invention. According to this feature of my invention, the stylus of the recording device is operated by a movable member of the regulator, thus dispensing with a separate diaphragm to operate the recorder and also increasing the amplitude of the stylus movements.

As shown in the drawings, the stylus 35 forms part of a recording device contained in a casing 37 carried by a post 36 projected from the bracket 32. To increase the amplitude of the stylus movements, the stylus is, for instance, secured to a lever 38, fulcrumed at one end upon a bracket 39 and connected at a shorter distance from the fulcrum than the stylus, with an operating rod 40 sliding in a guide sleeve 41. The lower end of the rod 40 rests upon a curved lug 42 having an involute face and secured to one of the levers 16 or 12 between the pivotal connection points 11 and 13. Owing to this arrangement, the operating rod 40 will always remain vertical, irrespective of the position of the lever 16 (or 12). The record is marked in the usual way on the sheet or strip 43 winding on the drum 45 driven by a clock-work 44. When the steam pressure increases, the swinging of the lever 16 about the fulcrum 13 by the rise of the rod 8 will raise the stylus 35 through the action of the lug 42 on the rod 40, the lower end of which slides on the curved face of the lug as the lever swings. The stylus will therefore mark on the strip 43 a line corresponding to the movement of the capsular spring 1. When thereupon the lever 16 is swung upward about the fulcrum 11 by the rise of the piston 22, the stylus is moved farther upward and marks a second line. Since the two movements which the lever 16 is given by the rod 8 and the piston 22 respectively, follow one another very closely, this second line will form a continuation of the first line and both lines together indicate

the increase of steam pressure. Should the pressure fall, the stylus 35 will move downward correspondingly, so that these pressure variations will be recorded. The improved regulator is exceedingly sensitive, the positions of the damper or other controller following even slight variations in the steam pressure. The record or diagram produced by the stylus 35 on the strip 43 will also show to the attendant the proper times for supplying fresh fuel, the crests of the record line indicating points at which the damper is almost entirely closed. The diagram further indicates (by showing the time required for the increase of steam pressure) how the intensity of combustion increases during a certain period and how much time elapsed between two successive supplies of fresh fuel, thereby affording a comprehensive and clear record of the combustion process and of the charging or stoking.

Any well-known or approved apparatus may be employed for obtaining a record of the temperature and of other features of the combustion process, and a comparison of these records with the pressure record on the strip 43 will show how the air supply should be varied in order to secure the best utilization of the fuel.

The great sensitiveness of the regulator and of the damper or other controlling device, obtained by my improved construction of the member exposed to boiler pressure, is also of great value in cases where the production of steam is governed, not by regulating the draft, as in the case described, but by regulating the supply of fuel through the medium of a slide controlled in any other suitable manner. These and other modifications are within the spirit of my invention as defined in the appended claims.

I claim as my invention:

1. In apparatus for correcting variations, a capsular spring arranged to follow such variations and composed of detachable sections so that their number may be readily increased or diminished, a variation-controlling regulator, an actuating member operatively connected with said regulator to shift the same, a valve governing the movement of said actuating member, an operative connection between said spring and the valve to shift the valve as the capsular spring expands or contracts, and an operative connection between the actuating member and the valve to restore the valve to its central position as the actuating member moves.

2. In apparatus for correcting variations, the combination of a movable member arranged to follow such variations, a rod carried by said member, a piston, a cylinder in which said piston is located, a slide valve controlling the movement of the piston, a movable fulcrum supported by the piston,

two rigidly connected levers mounted to rock in unison on said fulcrum, one of said levers having a pivotal connection with the said rod, and the other being operatively connected with the slide valve, and a variation-correcting regulator, operatively connected with said piston.

3. In apparatus for correcting variations, the combination of a movable member arranged to follow such variations, a rod carried by said member, a piston, a cylinder in which said piston is located, a slide valve controlling the movement of the piston, a movable fulcrum supported by the piston, two rigidly connected levers mounted to rock in unison on said fulcrum, one of said levers having a pivotal connection with the said rod, and the other extending beyond the axis of said pivotal connection, and being operatively connected with the slide valve from a point on the side of said pivotal connection opposite to the movable fulcrum, and a variation-correcting regulator, operatively connected with said piston.

25 4. In boiler furnaces, a capsular spring composed of detachable sections so that their number may be readily increased or diminished, means for exposing said spring to the pressure of the steam within the boiler, a device controlling combustion whereby the generation of steam is governed, an actuating member operatively connected with said controlling device, a valve govern-

ing the movement of said actuating member, an operative connection between said spring, 35 and the valve, and an operative connection between the valve and the actuating member.

5. In apparatus for correcting variations, a capsular spring arranged to follow such 40 variations and composed of detachable sections so that their number may be readily increased or diminished, a variation-controlling regulator, an actuating member operatively connected with said regulator, a 45 valve governing the movement of said actuating member, an operative connection between said spring and the valve, and an operative connection between the valve and the actuating member. 50

6. In apparatus for correcting variations, a movable member arranged to follow such variations, a variation-correcting regulator, a movable operative connection between said member and said regulator, and a recording device having a motion-receiving element in permanent contact with a movable portion of said operative connection. 55

In testimony whereof, I have signed this specification in the presence of two sub- 60 scribing witnesses.

JOHANN FRIEDRICH HEY.
